88 Claims. (Cl. 53—29)

ABSTRACT OF THE DISCLOSURE

A machine for simultaneously forming and filling packets with sugar or the like; the machine being designed to feed a strip of packaging material to a package forming and filling station where the strip is folded throughout its extent in a direction transversely to the feed direction into a generally channel-shaped trough by means of a plurality of spaced folder abutments mounted on a vertically reciprocating metering head. The metering head containing a plurality of valve controlled metering chambers each located between a pair of the folder abutments with valve control means so that the product is discharged from the metering chambers into the channel-shaped trough as the head moves downwardly. As the packages are thus being filled the folder abutments direct the folded edge of the channel-shaped strip downwardly between sealing rolls adapted to form the folded strip into a plurality of sealed product-filled packets.

This invention relates to a packaging machine and more particularly to a machine and method for simultaneously forming a package filling and sealing it while it is being formed.

It is an object of this invention to provide a machine and method for forming and filling packages at a very fast rate.

A further object of the invention resides in the provision of a machine of the type described which is capable of being operated at a very fast rate but which at the same time is designed such as to insure an absence of the material being fed, particularly pulverulent material, in and around the machine and particularly the sealing rolls and the sealed edges of the packages so that a good leakproof seal may be formed along said edges.

Another object of the invention is to provide a machine of the type described having a high production capacity but which can be operated with a minimum of power.

Still another object of the invention resides in the provision of a metering head on a machine of the type described which is designed to move vertically during the package filling cycle to obtain an improved material feeding operation at a high rate of speed.

Further objects and advantages of the invention relating to the unique construction and arrangement of the various components of the machine and ease with which they may be adjusted to insure the formation of a perfect package will become apparent from the following description and drawings in which:

FIG. 1 is a fragmentary front elevational view of the machine, with parts broken away and with the metering head assembly removed.

FIG. 2 is a fragmentary side elevational view of the machine as viewed from the left in FIG. 1 and with the platen in the elevated position.

FIG. 3 is a fragmentary perspective view of the paper reel mechanism at the rear side of the machine.

FIG. 4 is a fragmentary front elevational view showing the distributor and metering assembly.

FIG. 5 is a fragmentary side elevational view of the distributor and metering assembly as viewed from the right in FIG. 4 and with the platen in the lowered position.

FIG. 40a is an enlarged sectional view of a portion of the structure shown in FIG. 40.

FIG. 41 is a sectional view taken along the line 41—41 in FIG. 39.

FIG. 42 is a sectional view taken along the line 42—42 in FIG. 38.

FIG. 43 is a sectional view along the line 43—43 in FIG. 38.

FIG. 44 is a top view of the paper drive mechanism taken along the line 44—44 in FIG. 2.

FIG. 45 is a sectional view along the line 45—45 in FIG. 44.

FIG. 46 is a fragmentary view showing the drive arrangement for the paper feed roll.

FIG. 47 is a sectional view along the line 47—47 in FIG. 46.

FIG. 48 is a fragmentary longitudinal sectional view through the paper feed roll.

FIG. 49 is a fragmentary front elevational view of the knife head assembly.

FIG. 50 is a sectional view along the line 50—50 in FIG. 49.

FIG. 51 is a sectional view along the line 51—51 in FIG. 49.

FIG. 52 is an elevational view of the knife.

FIG. 53 is a fragmentary view, partly in section, of the paper reel support mechanism.

FIG. 54 is an end view of the mechanism illustrated in FIG. 53.

FIG. 55 is a sectional view along the line 55—55 in FIG. 53.

FIG. 56 is a plan view of the arbor on which the roll of paper is mounted.

FIG. 57 is an end view of the arbor illustrated in FIG. 56.

FIG. 58 is a plan view of the paper clamping bushing on the arbor.

FIG. 59 is an end view of the bushing illustrated in FIG. 58.

FIG. 60 is a generally schematic view illustrating the general arrangement of the various components of the machine.

FIGS. 61 through 66 illustrate sequentially the manner in which the sugar is metered, the paper is folded and sealed to form a package and the operation of the vacuum manifold and the pressurized air manifold to prevent the sugar from interfering with the formation of the package.

FIG. 67 is a timing diagram showing the relationship of the operating sequences of the basic components of the machine.

The machine of the present invention is adapted for feeding into packages being formed various types of flowable materials. The specific machine illustrated is designed for feeding pulverulent materials but the principle of construction and operation thereof are adapted for feeding semi-solid and solid materials as well. For example, while the machine is shown and described herein for purposes of illustration as a machine for forming and filling sugar packets of the type illustrated in FIG. 33a, it is adapted for use with all types of powdered or granular material. Likewise with minor modifications, primarily in the feed mechanism, the machine of this invention can be used for forming other similar packages and filling them with such materials as mustard, catsup, mayonnaise, tablets, etc. In the description which follows, the packages are formed of paper coated with a heat sealing material on one side thereof. Other materials such as plastic film, metal foil, etc. are likewise suitable as the stock from which the packages are formed and the sealant may be of the cold, pressure sensitive type.

General arrangement

Referring first to the generally schematic showing in FIG. 60, the machine comprises a hopper 10 having an outlet tube 12 which telescopes into the upper end of a sugar distributor 14. Distributor 14 discharges into and is mounted to reciprocate with a metering head 16. Head 16 is guided for reciprocation in a vertical direction by guide posts 18 (FIG. 2) and is reciprocated vertically by means of a drive cam 20 on the main drive shaft 76. Cam 20 engages a cam follower 24 mounted at the upper end of a post 26 on head 16.

As head 16 is shifted downwardly a hereinafter described valve mechanism within head 16 meters a predetermined amount of sugar from distributor 14 into a metering chamber. As the head descends the sugar is released from the metering chamber and as the head approaches its lowermost position, a rod 28 opens a dust trapdoor 30 on a chute 32 to allow the sugar from the metering chamber to fall downwardly. In the meantime the nose 34 of a paper folder 36 engages the center portion of a strip 38 of paper and folds the strip downwardly between a pair of spring leaves 40, and guides the folded strip further downwardly between a pair of sealing rolls 42, 44 which cut the folded paper strip 38 into individual packages and seal the edges thereof.

The paper for forming the packages is fed as a web 45 from a supply roll 46 around tensioning and straightening guide bars 48, 50, 52, 54 and between a rubber feed roll 56 and a steel idler roll 58 to a knife mechanism 60. The operation of the knife mechanism 60 is such that the paper strip 38 is sheared from the continuous web being fed from roll 46 just prior to the time that the nose 34 of folder 36 engages the central portion of the strip and drives it downwardly between the spring leaves 40. As will be described hereinafter, sealing rolls 42, 44 are adapted to seal the edges of the package while it is being formed and to shear the strip 38 to individual packages in a direction lengthwise of these rolls.

Drive arrangement

The power source for the machine comprises an electric motor 70 (FIGS. 1 and 2) which is connected through a speed reducing gearing 72 to an output shaft 74. Shaft 74 is connected with the main drive shaft 76 of the machine by means of a flexible coupling 78. Shaft 76 is journaled in pillow blocks 80 fixedly supported on the frame of the machine. The frame of the machine generally comprises four upright posts 82 interconnected at their upper ends by transverse bars 84, 86. Other fixed supports on the frame will be referred to as the description proceeds.

As is shown in FIG. 2, the free end of main shaft 76 has a crank 88 mounted thereon for rotative adjustment. Crank 88 is connected by a link 90 with a crank arm 92 on a clutch and brake mechanism 94. The connection between link 90 and crank arm 92 includes a block 96 mounted on arm 92 for adjustment lengthwise thereof by means of a slot 98 in arm 92. Thus with this arrangement the throw of crank arm 92 can be adjusted as desired.

The output shaft 100 of clutch and brake mechanism 94 has a sprocket 102 mounted thereon (FIG. 1). A chain 104 extends around sprocket 102 and around a sprocket 106 mounted on a shaft 108 which drives the rubber feed roll 56 (FIG. 48).

The main drive shaft 76 also has a sprocket 110 thereon connected by a chain 112 with a sprocket 114 on a jack shaft 116. Shaft 116 is journaled on the frame of the machine in pillow blocks 118. A sprocket 119 on jack shaft 116 is connected by a chain 120 with a sprocket 122 that drives the sealing rolls 42, 44 in a manner described more in detail hereinafter. A second sprocket 124 on jack shaft 116 is connected by a chain 126 with a sprocket 128 that reciprocates the knife assembly 60 vertically.

There are also mounted on jack shaft 116 a plurality of cams 129 for operating various microswitches and air

values the functions of which will be described herein-after.

Paper feed mechanism

Referring now to FIG. 3, the supply roll 46 of paper is supported on a shaft 130. Shaft 130 is in turn supported adjacent its opposite ends on rollers 132 which are journalled on rearwardly extending support bars 134 mounted on upright supports 136 on the frame of the machine. Referring also now to FIGS. 53 through 59, there is mounted on shaft 130 a collar 138 which supports one end of the core 140 on which the paper roll is wound. The other end of the core 140 is supported on a removable collar assembly 144. Collar assembly 144 comprises a shouldered bushing 146 which is interconnected with a disk 148 by means of a pair of parallel rods 150. Collar 138 is connected with a bushing 152 by a pair of parallel rods 154. Bushing 152 has a pair of studs 156 extending axially therefrom and through shouldered bushing 146 of the collar assembly 144. After the roll 46 is slipped over collar 138 and the collar assembly 144 is inserted into the other end of the roll with the studs 156 extending through the shouldered bushing 146, the two collars are tightened against opposite ends of the roll by means of nuts 158 threaded on studs 156. Collar 138 is splined to shaft 130 so that after the roll of paper 46 is mounted on the shaft 130 as described, it is constrained to rotate with the shaft 130. Shaft 130, together with the roll of paper 46 mounted thereon is adapted to be shifted transversely of the machine, that is, in a direction axially of the roll of paper, for proper alignment of the paper in the machine by means of a thumbscrew 160 which is adapted to shift a block 162 provided with a slot 164 in which the periphery of disk 148 is engaged. Thus, by rotating thumbscrew 160 in opposite directions the roll of paper 46 can be shifted axially in opposite directions in order to properly align the paper being fed through the machine.

As is illustrated in FIG. 60, the paper being fed by the rubber feed roll 56 is unwound from the bottom side of roll 46 and extends upwardly over tension bar 48. The function of bar 48 is to equalize the tension along the opposite edges of the paper being fed from the roll. Accordingly, each end of bar 48 is journalled in an arm 166 (FIG. 3). Each arm 166 is pivoted on a fixed support 168 as at 170, and is biased in a counterclockwise direction, as viewed in FIG. 3, by means of a tension spring 172. Since the arms 166 are adapted to pivot independently of one another, bar 148 will have a tendency to maintain uniform tension throughout the entire width of the paper being fed from roll 46. The web of paper being unwound from roll 46 then extends downwardly from around bar 48 and upwardly from around the second tension bar 50. At its opposite ends bar 50 is mounted on a pair of arms 174 pivotally supported, as at 176 on plates 178 which are fixedly mounted on a frame member 179 on the machine. The two arms 174 are interconnected by a crossbar 180 and a tension spring 182 extends from crossbar 180 to a fixedly supported post 184 on the frame of the machine. Spring 182 tends to rotate arms 174 in a clockwise direction, as viewed in FIG. 3, and thus exert a downward tension on the two runs of paper extending around the bar 50. The paper web then extends upwardly from around bar 50, around the front side of a guide bar 52 and then horizontally over guide bar 54. Guide bar 54 is mounted at each end in the side plates 186 of a fixed table having a horizontal bed portion 188. As is illustrated in FIG. 3, the web 45 of paper then extends horizontally in a direction toward the front of the machine between the rubber feed roll 56 and the steel idler roll 58 (FIG. 2).

One of the cams 129 previously referred to on jack shaft 116 intermittently actuates a microswitch which controls the energization of the clutch and brake mechanism 94. Mechanism 94 is designed such that when the crank arm 92 pivots in a clockwise direction, as viewed

in FIG. 2, a clutch is engaged to rotate the output shaft 100 and the sprocket 102 mounted thereon (FIG. 1). When crank arm 92 pivots in a counterclockwise direction, a brake is applied to output shaft 100 and the input shaft on which the arm 92 is mounted freewheels. Thus the chain 104 is caused to advance intermittently to thereby intermittently rotate feed roll 56 in a clockwise direction as viewed in FIG. 2. It will be appreciated that the increment of feed of the web 45 of paper by means of roll 56 can be adjusted by varying the point of connection between link 90 and arm 92 in a direction lengthwise of arm 92 in slot 98.

Referring now to FIGS. 46 through 48, it will be observed that idler roll 58 is journalled on a shaft 190. At each end shaft 190 is mounted in a lever 192 and each lever 192 is pivotally supported on a shaft 194 which extends through and is journalled in two side plates 186 of the paper feed table. At each end of rubber feed roll 56 there is journalled on the shaft 108 which supports the feed roll 56 a bearing block 196. A threaded stud 198 extends downwardly through each lever 192 and threads into bearing block 196. Each stud 198 is spring loaded, as indicated by the spring 200. Thus, by adjusting screws 198, the amount of pressure exerted on the paper web as it passes between rubber feed roll 56 and idler roll 58 can be varied as desired, as determined by the thickness of the paper being fed and other variables that might be encountered, such as the type of paper, etc.

Referring now to FIGS. 3 and 55, the brake and drag assembly for the roll feeding mechanism is illustrated. The brake comprises a brake drum 200 keyed to shaft 130 adjacent one end thereof and retained in an axially fixed position relative to the frame of the machine by means of guide blocks 202. A brake band 204 is anchored at one end as at 206 and extends around brake drum 200 with its free end having a spring 208 connected thereto. The other end of spring 208 is connected to the free end of a lever 210 which is secured to one end of a shaft 212. Shaft 212 is journalled at each end on brackets 178 and arm 214 is fixed on shaft 212 and extends upwardly therefrom toward roll 46. The free end of arm 214 has a block 216 thereon which bears against the outer periphery of roll 46. As is illustrated in FIG. 3, the end of arm 210 that is connected to shaft 212 is bifurcated as at 218 and provided with a clamping screw 220 to enable the arm to be rotatably adjusted on shaft 212.

With the above-described arrangement it will be observed that the brake tension on shaft 130 can be increased by pivoting arm 210 downwardly, or counterclockwise as viewed in FIG. 3, relative to shaft 212 to thus increase the tension of spring 208. Likewise it will be noted that as the size of the roll 46 decreases the braking effect on shaft 130 is decreased and the drag on the paper roll 46 by reason of block 216 is also decreased.

Knife assembly

The knife assembly 60 is best illustrated in FIGS. 1 and 49 through 51. The knife assembly as a whole is supported on the side plates 186 of the table. The main support for the knife assembly comprises a crossbar 230 which at each end is guided horizontally for fore-and-aft movement in guide slots 232 formed in side blocks 234 mounted on the upper edges of the side plates 186 of the paper feed table. The fore-and-aft adjustment of crossbar 230 is effected by adjusting screws 236 (FIG. 50) which are journalled in lugs 238 and threaded into lugs 240 fixed to opposite ends of the crossbar 230. With this arrangement it will be seen that by rotating the adjusting screws 236, the crossbar 230 and the structure supported thereby can be advanced or retracted in a direction fore and aft of the machine relative to the paper web being fed therethrough.

Referring particularly to FIGS. 49 and 51, there is secured to the underside of crossbar 230 a pair of depending side plates 242, the lower ends of which are intercon-

nected by a transversely extending crossbar 244. A stationary knife blade 245 is mounted on the upper face of crossbar 244 and extends in a direction forwardly therefrom. Also mounted on the upper face of crossbar 244 is a paper guide plate 247 which serves to guide the web of paper being fed from roll 46 from between the feed roll 56 and the idler roll 58 to the knife assembly. This arrangement is illustrated in FIG. 45. Guide plate 247 along its rear edge is slotted as at 248 so that it is adapted to telescope between similarly shaped lugs on a stationary paper guide plate 250.

There is also mounted on the depending side plates 242 an upper paper guide 252 which is spaced above the knife plate 245 and the paper guide plate 247. Upper guide plate 252 is secured to the underside of a narrow crossbar 254 which is in turn secured to the inner side of the depending side plates 242. At its rear edge the upper guide plate 252 is slotted as shown at 249 in FIG. 50 to receive therebetween the correspondingly shaped lugs on a stationary upper guide plate 256 on the table of the machine (FIG. 44).

On the top side of the main crossbar 230 of the knife assembly there is mounted a pair of upstanding side plates 258. These side plates are interconnected at their upper end by a top cross plate 260. The sprocket 128 which reciprocates the knife head is mounted on a shaft 262 which is journalled in the upright plates 258. A cam 264 is keyed to the shaft intermediate the two plates 258 and is adapted to engage a small cross shaft 266 journalled in depending brackets 268 on a crosshead 270. At its opposite ends crosshead 270 is fixed to a pair of upright rods 272. Rods 272 are interconnected at their upper ends by a crossbar 274. At their lower ends rods 272 support a knife head 276. The knife blade 278 is fixed to the front face of knife head 276.

As will be observed from the showing in FIG. 51, when shaft 262 is rotated in a clockwise direction, cam 264 engages rod 266 to shift the knife head 276 upwardly and thus retract the knife blade 278. When the shaft 266 rides off the high side of cam 264, that is, at the radial shoulder 280, the whole knife head is shifted downwardly with a rapid movement under the influence of compression springs 282 which encircle guide rods 284. The lower ends of guide rods 284 are secured to the knife head 276 and their upper ends are slidably guided in apertures in the top cross plate 260. The upper ends of springs 282 bear against the underside of the top cross plate 260 and the lower ends of these springs bear against bushings 286, which are adjustably locked on the guide rods 284.

The extent of downward movement of knife head 276 is limited by a rubber bumper block 288 which is mounted for vertical adjustment on the crossbar 274 and is adapted to engage the top side of cross plate 260.

Referring now to FIG. 51, the chain 126 which extends around the drive sprocket 124 for the knife assembly on shaft 116 extends around sprocket 128 and also extends around an idler sprocket 290. Sprocket 290 is an idler sprocket carried by a block 292 slidably mounted on a pair of guide pins 294. Block 292 is urged in a direction away from sprockets 124 and 128 by means of compression springs 296. This effectively takes all the slack out of chain 126.

Since sprocket 124 is mounted on the continuously rotating jack shaft 116, it follows that the main shaft 262 of the knife mechanism rotates continuously. Thus knife head 276 and the blade 278 mounted thereon reciprocate vertically continuously under the control of cam 264. The line of cutoff on the paper web can be accurately controlled by adjusting screws 236 to shift the whole knife head assembly in a fore-and-aft direction. Since the sprocket 124 is fixed and the sprocket 128 moves in a fore-and-aft direction with the knife head assembly, the idler sprocket 290 accommodates for the movement of sprocket 128 in a fore-and-aft direction in response to adjustment of the knife head assembly.

Referring now to FIGS. 45 and 50, knife head 276 is provided with three slots 30 therein which extend down from the upper face thereof. Within each of these slots there is guided a nut 302 into which a stud 304 is threaded. Studs 304 extend through knife blade 278 and springs 306, which are compressed between the closed end of slots 300 and the nuts 302, urge the knife blade 278 against the front face of knife head 276. Knife blade 278 is accurately located on knife head 276 by means of dowel pins 308. Studs 304 and springs 306 are utilized merely for the purpose of controlling the pressure between the engaged edges of knife blade 278 and knife plate 245.

The shape of knife blade 278 is best illustrated in FIG. 52. The lower edge of knife blade 278 provides the cutting edge for the blade and is defined by two portions 310 which slope upwardly from opposite edges of the knife blade toward the center. At the extreme opposite edges a pair of depending lugs 312 are provided. The purpose of lugs 312 is to prevent complete vertical separation between the cutting edges of knife plate 245 and knife blade 278.

The upwardly sloping cutting edge portions 310 of knife blade 278 form an important feature of the present invention. With the knife edge formed in this fashion, as distinguished from a single inclined cutting edge, experience has shown that the tendency for the paper web to twist as it is being cut is eliminated. In addition, the stroke of the knife blade can be materially reduced by forming the cutting edge with two upwardly sloping portions, as distinguished from a knife blade wherein the cutting edge slopes continuously in one direction from one edge to the other.

With the above-described arrangement, the operation of the knife head assembly is obvious. Since the jack shaft 116 on which the drive sprocket 124 is mounted rotates continuously while the machine is in operation, it is apparent that shaft 262 and cam 264 likewise rotate continuously. Thus the crosshead 270 is intermittently raised by cam 264 and driven downwardly intermittently by springs 282 when the cross shaft 266 rides off the high end of cam 264, as at 280. In turn knife head 276 and the knife blade 278 mounted thereon are intermittently reciprocated vertically since the knife head is secured to the lower ends of the spring retainer guide pins 284. As the knife blade 278 descends, the laterally outermost portions of the sloping cutting edges 310 engage the paper web 45 adjacent its outer edges and shear the paper in a direction inwardly from its outer edges toward the center at each side thereof into a strip 38. As indicated previously, since the two outside edges of the paper web are engaged simultaneously, any tendency for the paper to twist as it is being sheared is eliminated. Although not illustrated in the drawings, knife blade 278 has a slight bow in it from one end to the other, the bow extending in the direction of the stationary knife plate 245. This bow in the knife blade is necessary in view of the fact that the blade is cutting inwardly from opposite ends, rather than continuously from one end to the other. It will be appreciated, however, that as the knife blade 278 descends, springs 306 resiliently bias the cutting edge of knife blade 278 against the cutting edge of the horizontal knife plate 245.

Sugar feed structure

Referring now to FIGS. 6 and 7, hopper 10 is of conventional design with side walls which taper inwardly toward the outlet tube 12 which is fixed thereto. Tube 12 extends upwardly through hopper 10 and adjacent the lower end of the hopper, tube 12 is provided with a plurality of circumferentially spaced openings 320 which are designed to permit the flow of sugar from within hopper 10 into tube 12 and downwardly toward the lower end thereof. The lower end of tube 12 is controlled by a valve 322 in the form of a cone affixed to the lower end 75 of a rod 324. The upper end of rod 324 is connected by

means of a coupling 326 with the piston rod 328 of an air cylinder 330. Cylinder 330 is operated by an electric eye mechanism hereinafter described, to reciprocate rod 324 and thereby shift valve 322 upwardly to a position closing the lower end of tube 12.

As indicated previously, sugar distributor 14 is telescopically arranged over the lower end of tube 12. Distributor 14 comprises a housing 331 forming a trapezoidal chamber 332 into which the lower end of tube 12 discharges. At the upper end of housing 331 there is arranged a collar 334 which extends circumferentially around tube 12 and has a slight clearance therewith. As sugar is discharged into housing 331, the volume of chamber 332 is reduced and air is permitted to exhaust upwardly through collar 334. However any sugar dust that might be entrapped with the exhausting air will be directed into a vacuum line 336 connected with the inner periphery of collar 334 and thus prevent such sugar dust from escaping into the air surrounding the machine.

Hopper 10 is fixedly mounted on the frame of the machine by a bracket structure generally indicated 338. The lower end of bracket structure 338 is fastened to a heavy platen 340 which extends transversely of the machine and supported adjacent its opposite ends on the crossbars 86 (FIG. 2).

The lower end of distributor housing 331 is closed by a plate 342 having two apertures 344 extending downwardly therethrough. Plate 342 forms a guideway for a shiftable valve plate 346 which, in one position thereof, has apertures 348 therein which register with apertures 344 in plate 342. Valve plate 346 is adapted to be shifted in a longitudinal direction to move aperture 348 out of registration with aperture 344 and thus close the lower end of sugar distributor housing 331. Along the front and rear side walls of housing 331, at the lower end thereof, there is mounted a pair of sloping side plates 350 which, together with a triangular center piece 352, is adapted to discharge the sugar from within housing 331 through the registering apertures 344, 348 downwardly through apertures 354, 356 in plates 358, 360, respectively. Within each aperture 356 there is arranged a triangular divider 362 which divides the stream of sugar flowing through each aperture 354 into two streams.

Valve plate 346 is provided with a handle 364 which enables the valve plate to be shifted manually between opened and closed positions. Valve plate 346 is not reciprocated during operation of the machine; its only function is to effectively prevent discharge of sugar from distributor housing 331 when the machine is being adjusted for some purpose or the flow of sugar is not required.

On one side of distributor housing 331 there is located an electric eye mechanism 366 which includes a light source 368. When the light source 368 is blocked by reason of the fact that the quantity of sugar in housing 331 rises to a level above light source 368, electric eye mechanism 366 is designed to operate cylinder 30 to raise valve 322 to a position closing the lower end of outlet tube 12 from hopper 10. The flow of sugar to housing 331 is thus arrested and valve 322 remains in a closed position until the level of sugar in housing 331 drops below the light source 368, at which time cylinder 330 is again operated to lower valve 322 and again permit discharge of sugar from hopper 10 into distributor 14.

Metering mechanism

From the distributor 14, the sugar is discharged downwardly through the aperture 356 in plate 360 into the metering head 16. Metering head 16 (FIGS. 8 and 9) comprises a rear plate 370, a front plate 372, and end plates 374 secured together to form a generally rectangular housing. Each side plate 374 has secured to the upper side edges thereof bars 375 which in turn are mounted on the bottom side of a platen 376. Platen 376 is guided for vertical movement by means of linear ball bushings 380 on guide posts 18 fixedly mounted on platen 340 (FIGS.

2 and 4). Platen 376 is biased in an upwardly direction by means of compression springs 382 which circle tubes 384 secured to the lower ends of guide pins 18. The upper ends of springs 382 bear against the underside of platen 376 and the lower ends of these compression springs bear against collars 386 adjustably mounted on tubes 384. Tubes 384 are connected to the lower ends of guide posts 18.

Platen 376 is shifted in a downwardly direction on guide post 18 by means of cam 20 on the main shaft 76 (FIG. 5). Platen 376 is interconnected with cam 20 by the vertically extensible post 26 having a cam follower in the form of the roller 24 journaled at the upper end thereof. Post 26 comprises two members 396 and 398 secured together by screws 400. Screws 400 extend through vertically extending slots 402 in bar 396, which enables the bar 396 to be raised and lowered with respect to bar 398. The extensibility of post 26 enables adjustment of platen 376 in a vertical direction.

Referring now to FIGS. 8 and 9, it will be observed that within the rectangular housing forming the metering head 16 there is mounted a metering mechanism 404. This metering mechanism includes a plate 406 extending along the inner side of back plate 370 and along the upper edge thereof. Plate 406 is fashioned with a plurality of notches 408 which register with the apertures 356 in plate 360 (FIG. 9). A second plate 410 is also mounted on the inner side of back plate 370 and is spaced below plate 406. Plate 410 likewise has notches 412 formed therein which register vertically with the notches 408 in plate 406 and notches 412 in plate 410. However, plate 414 is reversely positioned relative to plates 406 and 410 such that the open ends of notches 416 project forwardly rather than rearwardly as is the case with plates 406 and 410. Thus the web portions 418 of plate 414 lie flush against the inner surface of back plate 370.

Within each notch 416 in plate 414 there is adjustably mounted a block 420 connected to one end of a rod 422 (FIGS. 9 and 13). Each rod 422 extends through a guide bar 424 and at their free ends rods 422 extend through front plate 372. The outer ends of rods 422 are threaded to receive nuts 426. A compression spring 428 around each rod 422 bears at one end against the inner face of front plates 372 and at their other ends on a collar 430 adjustably fixed on rods 422. This arrangement enables the blocks 420 to be adjusted in notches 416 in a direction toward and away from the web portions 418 and thus determines the effective volume of the notches 416. Notches 416 thus form metering chambers which can be adjusted in volume by adjusting the nuts 426 on the ends of rods 422.

A pair of slide valves 432 and 434 are provided for alternately opening and closing the upper and lower ends of metering chambers 416. Each slide valve 432 is pinned as at 435 to a crossbar 436 and each slide valve 434 is pinned to a crossbar 438. Crossbar 436 is connected at its opposite ends by screws 440 to a pair of guide bars 442 (FIG. 8). Guide bars 442 are mounted for axial reciprocation in front plate 372 and rear plate 370. At their forward ends guide bars 442 are interconnected by a crossbar 444. The crossbar 438 for the lower slide valves 434 is likewise connected at its opposite ends to a pair of guide bars 446, the forward ends of which are connected by a crossbar 448.

Between each of the successive slide valves 432, 434 there are arranged shim plates 450 (FIG. 15). These shim plates have a thickness slightly greater than slide valves 432, 434 and form rectilinear guideways for the slide valves. At their rear ends, shims 450 are clamped between the upper face of metering chamber plate 414 and lower faces of plate 406 and between the lower faces

of bar 414 and the upper face of plate 410 by screws 452 (FIGS. 13 and 15). At their forward ends shims 450 are clamped against the top and bottom faces of guide bar 424 by transversely extending straps 454 and screws 456. Thus guide bar 424 is actually supported in a position spaced forwardly from rear plate 370 by spacer plates 450.

The upper crossbar 444 has an arm 460 connected thereto, and the lower crossbar 448 likewise has an arm 462 mounted thereon. These arms project forwardly from their respective crossbars and are provided with rollers 464 at their free ends (FIG. 9). Referring now to FIG. 5, roller 464 on arm 460 is engaged within a slot 466 in a lever 468 and roller 464 on arm 462 is engaged in a slot 470 in a lever 472. Levers 468 and 472 extend upwardly and are fashioned with lugs 474 by means of which they are pivotally supported on a shaft 476 mounted in a pair of spaced brackets 478 which depend from the lower side of platen 340 (FIG. 6). The upper ends of levers 468 and 472 have rollers 480 (FIG. 4) journaled thereon. Rollers 480 are adapted to engage in cam grooves 482 formed on opposite sides of cam 20 by cam members 481 and 483. Cam grooves 482 are so located on the opposite sides of cam 20 such that when cam 20 is rotated, levers 468 and 472 are simultaneously oscillated about the shaft 476 in opposite directions. This causes the two valve plates 432, 434 to be alternately reciprocated such that when valve plate 432 closes the upper end of metering chambers 416, the lower valve 434 opens the lower end of metering chambers 416. The operation is such that when the upper end of the metering chambers 416 are open, the metering chambers are permitted to fill with sugar. Thereafter, when the upper valves 432 close the upper ends of metering chambers 416 and the lower valves 434 open the lower ends of metering chambers 416, the sugar in each metering chamber 416 is adapted to discharge downwardly through the metering head 16.

The lower end of the rectangular housing forming the metering head 16 is closed by a bottom manifold plate 484 (FIGS. 9 and 11). Manifold plate 484 is fashioned with a generally triangularly shaped cavity 466 therein which opens at the bottom face thereof as at 488. Recess 486 is covered at the top by a plate 490 having a longitudinal slot 492 therein. Slot 492 registers with a similar slot 494 in a funnel plate 496 which is attached to the bottom side of the lower spacer plates 450. Each of the upper and lower slide valves 432, 434 has a plurality of openings 498 therein (FIG. 14) which are located between blocks 420 and guide bars 424. Thus, any sugar that escapes from the vertical passageways in the metering head formed by apertures 408 and 412 in combination with metering chambers 416 by reason of reciprocation of the slide valves is permitted to drop freely downwardly onto the funnel plate 496 and through the registering slots 494 and 492 into the recess 486 of the bottom manifold plate 484. As is shown in FIG. 11, the forward edge of bottom manifold plate 484 is fashioned with a plurality of notches 500 which register with the vertical sugar passageways in the metering head.

As will be described more fully hereinafter, recess 486 in manifold plate 484 is connected through aperture 488 with a source of vacuum, so that any sugar which drops into recess 486 is conveyed away from the metering head.

Dust trap mechanism

On the underside of manifold plate 484 there is secured a second manifold plate 502 (FIGS. 9 and 12). Manifold plate 502 has a recess 504 in the top side thereof which communicates on the one hand with the aperture 488 in manifold plate 484 and on the other hand with a second aperture 506 through manifold plate 484 to which a vacuum line 508 is connected. Thus, when line 508 is connected to a source of vacuum, any sugar or

other particles collecting in recess 486 of manifold plate 484 is sucked downwardly into the recess 504 of the lowermost manifold plate 502 through aperture 488 and then upwardly through opening 506 into the vacuum line 508.

On the bottom side of manifold plate 502 there is secured a third manifold 510 (FIGS. 9 and 10). Manifold 510 has four apertures 512 opening on the front face thereof which are connected with a longitudinal passageway 514 by slots 516. Passageway 514 in turn is connected by elongated apertures 518 which register with apertures 520 on the bottom wall of manifold plate 502. Apertures 520 in turn open into the recess 504 of manifold plate 502, and thus the vacuum line 508 is connected to the apertures 512 in manifold housing 510. The back side of manifold 510 has a cover plate 519.

Referring to FIG. 9, it will be noted that the lower edge of rear plate 370 extends downwardly beyond manifold plate 484 and terminates in a tapered edge 522. The inner side of rear plate 370 adjacent the lower portion thereof forms one side wall of a sugar discharge chute 32. The two side walls of each chute 32 are formed by the sides of the paper folders 36. Paper folders 36 (FIGS. 12, 19 and 20) are mounted on the inner face of the lower portion of rear plate 370 of the metering head in spaced-apart relation (see FIG. 12). As is illustrated in FIGS. 19 and 20, each paper folder 36 has a body portion 524, the lower end of which tapers to a point as illustrated to form the nose portion 34 of the folder. The nose portion 34 actually comprises two spaced-apart wedges 526 with a clearance space between them. Folders 36 are mounted on the rear plate 370 of the metering housing by screws passing through holes 528 drilled through the paper folders. At their upper ends each paper folder is fashioned with a forwardly extending lug 530 provided with a horizontally extending through opening 532 therein, by means of which the trapdoors 30 are pivotally supported on the underside of the metering head between the spaced-apart folders 36, as by pins 534.

The construction of each trapdoor is illustrated in FIGS. 9, 21, 22 and 23. Each trapdoor assembly includes a tubular portion 535, the forward end of which in the closed position of the trapdoor is adapted to register with the opening 512 in manifold plate 510 (FIG. 9). Tubular portion 535 is connected with a hollow body portion 536 by a plate 538 and screws 540. Body portion 536 has a flat rear wall 542 which, in the closed position of the trapdoor, as illustrated in FIG. 9, engages the inner face of rear plate 370 of the metering head to close the lower end of chutes 32. The front side of each trapdoor 30 is closed by a cover plate 544, the inner face of which is grooved as at 546 so that the hollow chamber within the trapdoor assembly is open at the lower tip thereof as at 548. Plate 544 is secured to the body portion 536 of the trapdoor assembly by screws 550.

Each trapdoor assembly 30 is normally retained in the position illustrated in FIG. 9, closing the lower end of chutes 32, by tension springs 552 having one end connected to screws 554 on the paper folders 36 and the other ends connected to screws 556 at each side of the trapdoor assembly.

It will be appreciated that with the trapdoors 30 in the position illustrated in FIG. 9, where the tubular portion 535 registers with the opening 512 in manifold housing 510, the interior of the trapdoor assemblies communicates with the vacuum line 508 and thus a vacuum is present at the lower tip ends of each trapdoor as at 548.

Referring now to FIG. 5, the means for operating the dust trap mechanism is there illustrated. In the condition shown in FIG. 5, cam roller 24 is riding on the high side of cam 20 and platen 376 is therefore in its lowermost position. As a matter of fact the portion 560 which cam follower 24 is shown engaging in FIG. 5 is formed as an arc struck about the center of shaft 76 as its axis so that the portion 560 of cam 390 is actually

a dwell portion which momentarily retains platen 376 for a short period of time in its lowermost position.

The means for operating the trapdoor 30 comprise a cam 562 adjustably clamped to jack shaft 116 and adapted to be engaged by a cam follower roller 564 at one end of a bell crank 566. Crank 566 is keyed to shaft 194 which, as mentioned previously, is the shaft on which the levers 192 that support the paper feed idler roll 58 are journaled. The end of shaft 194 opposite that shown in FIG. 5 has an arm 568 (FIG. 44) keyed thereto which is parallel to the arm 570 of bell crank 566. The free ends of arms 570 and 568 are interconnected by a rod 28 which extends transversely below each of the trapdoors 30. As is seen in FIG. 5, rod 28 is spaced forwardly of the pivot axis 534 of the trapdoors 30.

Bell crank 566 is biased by a spring 574 in a clockwise direction, as viewed in FIG. 5. Thus spring 574 normally urges rod 28 in an upward direction toward the metering head 16. As pointed out above, in the condition of the assembly shown in FIG. 5, platen 376, and therefore metering head 16, are in the lowermost position. As illustrated, cam roller 564 is on the high side of cam 562. On the upstroke of head 16, head 16 moves upward at a rate faster than rod 28 is caused to move upwardly by reason of cam roller 564 riding off at the high side of cam 562 and thus the trapdoors 30 remain closed. However, on the downstroke of head 16 when cam roller 564 is in engagement with the rise portion 562a on cam 562, rod 28 engages the lower side of the tubular section 535 of trapdoors 30 and thus pivots the trapdoors about pins 534 in a clockwise direction. Pivotal movement of the trapdoors 30 in a clockwise direction is limited by a pair of rubber bumpers 576 on the underside of metering head 16 at each end thereof. The manner in which the opening and closing of the trapdoors 30 is synchronized with the raising and lowering of the metering head will be described hereinafter.

Paper folding mechanism and air nozzle structure

As pointed out previously and as shown in FIG. 9, the paper folders 36 are fixedly mounted on metering head 16 and terminate at their lower ends in tapered nose portions 34. Extending transversely of the machine in fixed position below the paper folders 36, there is arranged a rectangular frame 580 (FIG. 1) along the longitudinal edges of which are mounted a pair of spring leaves 40 previously referred to in connection with FIG. 60. The free edges 586 of spring leaves 40 are overlapped as shown in FIG. 40, the overlapped portions of the two spring leaves being located centrally below the nose portions 34 of the knife folders 36.

As the paper web 45 is fed through the knife mechanism by the feed roll 56, the leading end thereof passes into a position overlying spring leaves 40. To assure that the opposite side edges of the paper web will not curl up as it is fed through the knife mechanism, there is provided a pair of paper hold-downs 588 in the form of spring leaves adjacent the opposite ends of the knife head (FIGS. 49, 50 and 51).

The functions of the spring leaves 40 are several. These spring leaves form a resilient platform for the paper strip 38 after it is sheared by the knife mechanism from the web 45. In addition, spring leaves 40 cooperate with the nose portions 34 of the folders 36 to assure proper folding of the paper strip. In other words, spring leaves 40 wipe the paper upwardly along the edges of the two spaced-apart wedges 526 of the paper folders 36. The spring leaves 40 resiliently press the paper strip against the edges of the wedges 526 of the paper folders so that between each successive set of wedges 526 a sealed chamber is progressively formed to receive the sugar being discharged from the metering head as the head and the paper folders descend.

Frame 580 actually comprises a manifold structure, shown in FIGS. 38 through 43. A pair of conduits 590,

592 extend from a source of air under pressure not illustrated to this manifold structure. The rear side of frame 580 comprises an upper section 594 and a lower section 596 separated by a sealing gasket 595. The upper section 594 is fashioned with a manifold chamber 598 which extends for a major portion of its length and a second chamber 600 which communicates with a manifold chamber 602 in the lower member 596 through an aperture 604. As is shown in FIGS. 38 and 41, conduit 490 is connected by means of a passageway 606 with the manifold chamber 598 and conduit 592 is connected by means of a passageway 608 with manifold chamber 600. Along its inner edge the upper member 594 of the manifold is provided with a plurality of orifices 610 which, as shown in FIG. 40a, are inclined upwardly slightly at an angle of about 10°. The lower member 596 of the manifold is provided with two sets of orifices along its length. One set of orifices, designated 612, extends inwardly at a slightly downward angle along the inner side of member 596, and the other set of orifices, designated 614, extends through the bottom wall of member 596 at an angle of approximately 45° and are directed inwardly of frame 580. As will be explained more fully hereinafter, the provision of separate air conduits 590 and 592 is desired because it is essential to direct air through the orifices 610 and the orifices 612 and 614 at different time intervals.

Sealing roll mechanism

As the packages are formed by the folders, the folded edge of the paper strip 38 is directed downwardly between a pair of sealing rolls 42, 44. The sealing rolls and their mounting structure are best illustrated in FIGS. 24, 25, 26 and 29 through 33. Each sealing roll comprises a hollow shaft 620 in which is inserted a heater 622 (FIGS. 24 and 25). Each shaft 620 is fashioned with a shoulder 624 adjacent one end and a threaded portion 626 adjacent its opposite end. A key 628 extends between shoulder 624 and threaded section 626 so as to engage with a keyway 630 in the sealing roll sections 632. Each sealing roll section 632 is of cylindrical shape and at opposite ends thereof is fashioned with a peripheral flange 634. At diametrically opposite portions the two end flanges 634 are connected by an axially extending rib 636. Sections 632 on the two shafts 620 are arranged such that the flanges 634 of each section 632 on one shaft register with the flanges 634 of each section 632 on the other shaft.

The two shafts 620 are interconnected by gears 638, 640 (FIG. 24) such that when the sections 632 rotate, the ribs 636 also register with one another between the two rolls. The inner face of the paper from which the packages are formed is preferably coated with a heat-sealing adhesive, although a pressure-sensitive type of adhesive may be used if desired. The flanges 634 at the opposite ends of the sealing roll section 632 are adapted to form the seals at the ends of the package being formed, and the ribs 636 are adapted to seal the package at the end thereof opposite the fold in the package.

Between successive sealing roll sections 632 there is arranged a spacer 637 and a circular knife 639. The spacers and knives are arranged as shown in FIG. 24 so that as the paper strip 38 is fed downwardly between the sealing rolls it is sheared into individual packages between the adjacent flanges 634 of the sealing roll sections 632. The packages formed by the machine are designated 642 in FIG. 33a. The sealed edges 644 along each side of the package are formed by the flanges 634 of the sealing roll section 632 and the sealed edge 646 which is opposite the folded edge 648 of the package is formed by the registering ribs 636 of the sealing rolls.

Referring now to FIGS. 24 and 25, gear 638 is a driven gear which in turn drives gear 640. Gear 638 provides a direct drive to the shaft 620 for the rear sealing roll 44. This shaft is supported at each end in graphite bushings 650 (FIG. 26) which are mounted in bearing blocks

652. Bearing blocks 652 are secured to a sealing roll frame 654 by screws 656. Frame 654 includes a rear plate 658 and front plate 660 (FIG. 24). Bearing blocks 652 extend between plates 658 and 660. Plates 658 and 660 are also interconnected by a bearing plate 662. The terminal boxes 664 for the heaters 622 within shafts 620 are supported on crossbars 666, which are connected at their opposite ends to the rear and front frame plates 658, 660, respectively. Each terminal box 664 has carbon brushes 668 projecting therefrom which are spring biased to engage terminal caps at the ends of the heaters to provide electrical contact with the resistance elements within the heaters.

Shaft 620 for the front sealing roll 42 is supported at each end in carbon bushings 670 mounted in bearing blocks 672. Bearing blocks 672 are pivotally supported on a shaft 674 which is mounted at opposite ends on forward extensions 676 of bearing blocks 652. Each bearing block 672 has a plate 678 (FIG. 26) mounted on the front face thereof as by screws 680, through which a micro-adjusting screw 682 is threaded. Screw 682 has two threaded portions 684 and 686 of different pitches. Threaded portion 684 engages a similar thread on plate 678 and thread 686 engages a corresponding thread on a tubular nut 688, which is prevented from rotating by means of a dog 690 engaging a slot 692 in bearing block 672. Two springs 694 are arranged between plates 678 and the inner end of adjusting screws 696. Springs 694 bias the ends of sealing roll 42 toward sealing roll 44 and the extent to which sealing roll 42 is permitted to move in a direction toward sealing roll 44 is limited by the tubular nut 688 which at its free end engages against the face 698 of bearing block 652. The provision of the differential threads 684, 686 enables a micro-adjustment of bearing blocks 672 toward and away from bearing blocks 652 about shaft 674 as a pivot. Thus, a desirable clearance space between the peripheral flanges 634 on the opposed bearing roll sections 632 on the two shafts 620 can be controlled very accurately in thickness. In practice the flanges 634 of the opposed sealing roll sections 632 are spaced apart by means of adjusting screws 682 a distance corresponding to slightly less than double the thickness of the paper strip from which the packages are being formed. With this arrangement, as the folded paper strip is fed downwardly between the sealing rolls, the edges 644 and 646 of the packages being formed are slightly compressed and thereby effectively form a leak-proof package.

The mounting arrangement for the two sealing rolls, as shown in FIG. 26, forms an important feature of the present invention. Experience has shown that best results are obtained when the registering flanges of the two sets of sealing rolls are spaced apart a predetermined distance as distinguished from those arrangements wherein the registering flanges of sealing rolls are caused to contact one another. When the registering flanges of sealing rolls are held in tight contacting relation, there is a tendency to shear or crush the edges of both end packages being formed leaving the edges of the middle packages unsealed due to the bowing action of the sealing roll shafts under the load. Springs 694 provide the necessary give to allow the sealing rolls to separate to accommodate an obstruction passing therebetween.

Drive mechanism for sealing roll

The arrangement for driving the sealing rolls at the proper speed and in timed relation with the other elements of the machine is illustrated primarily in FIGS. 34 through 37. This arrangement is also generally illustrated in FIGS. 1 and 2. The power for driving the sealing rolls is derived from the jack shaft 116. At one end thereof, the left end as viewed in FIG. 1, there is secured thereto a clutch block 700. Block 700 is connected to the end of jack shaft 116 by a pair of studs 702. The portion of jack shaft 116 to which clutch block 700 is secured is

of reduced diameter, as indicated at 704 (FIG. 37). Sprocket 119 is journalled on the reduced portion 704 of shaft 116 by a bushing 705 and is connected to a clutch plate 706 by screws 708. It will be observed that the assembly of sprocket 119 and clutch plate 706 has a close fit between the shoulder 710 on shaft 116 and the inner face 712 of clutch block 700.

Clutch block 700 is formed with two counterbores 714, 716 which are located at different distances from the central axis of jack shaft 116. Clutch plate 706 is formed with a pair of conical recesses 718, 720 which in one position thereof register with counterbores 714 and 716, respectively. Within each counterbore 714, 716 there is arranged a ball detent 722 which is biased toward clutch plate 706 by a spring 724. Each detent 722 is preferably fashioned with a stem 726. Each stem 726 extends axially through an adjusting screw 728. At their outer ends the stems 726 bear against a bar 730 which is biased against the ends of stems 726 by a spring 732. Screws 728 permit adjustment of the biasing force on detents 722 and thus determine the force required to compel clutch block 700 to slip relative to clutch plate 706.

As previously mentioned, sprocket 119 through a mechanism about to be described, rotates the sealing rolls. Thus if the sealing rolls become jammed for any reason, they simply stop rotating while the clutch block 700 rotates idly relative to clutch plate 706. When this occurs, the ball detents 722 ride out of the conical recesses 718, 720 and acting through the stems 726 shift bar 730 in a direction outwardly. If desired a micro-switch 733 may be arranged to be tripped by bar 730 to stop the machine when this occurs.

As is shown in FIG. 34, the chain 120 which interconnects sprocket 119 with sprocket 122 is trained around a plurality of six sprockets designated 734, 736, 738, 740, 742 and 744. All of these sprockets are in the form of idlers. Sprockets 734 and 736 are fixedly mounted on a support bar 746, and sprockets 742 and 744 are likewise fixedly mounted on a support bar 748. Support bars 746 and 748 are in turn fixedly mounted on an upright support bar 750 on the machine frame. Sprocket 738 is mounted on a slide 752 which is guided for movement between support bars 746 and 748. Sprocket 740 is mounted on a bracket 754 which is adjustably secured to slide 752 by means of slots 746 and retaining screws 758.

Referring now to FIG. 36, it will be noted that slide 752 has a lug 760 projecting from the inner face thereof and adjusting screw 762 provided with a knob 764 at one end thereof is threaded through lug 760. The other end of adjusting screw 762 is rotatably connected to a lug 766 projecting from the rear face of upright bar 750 by a shoulder screw 768. With this arrangement it will be observed that as knob 764 is rotated in one direction or the other, slide 752 together with bracket 754 and the two sprockets 738, 740 mounted thereon are shifted laterally relative to the remaining four sprockets. Thus, as slide 752 is adjusted by means of screw 762 while sprocket 119 remains stationary, a portion of the chain is simply fed from one set of three sprockets to the other set of three sprockets, and in so being fed the chain rotates sprocket 122. This enables repositioning of sprocket 122 relative to sprocket 119 while the machine is operating. In turn, as will be pointed out hereinafter, this enables sealing rolls 42, 44 to be adjusted relative to the nose 34 of folder 32 so that the transverse ribs 636 on the sealing roll sections will be properly synchronized to produce the seams 646 in the packages being formed at the desired location.

Referring now to FIGS. 24, 25, 27, 28 and 35, sprocket 122 is mounted on a shaft 770, one end of which is journalled as by a bearing 772 (FIG. 28) in the upright support bracket 750. The opposite end of shaft 770 extends through upright bracket 774 (FIG. 35) in which it is journalled by means of a bearing 776. The projecting

end 778 of shaft 770 has clamped thereon a block 780 provided with an L-shaped extension 782 along one side thereof (FIG. 35). Block 780 is split as at 782 (FIG. 27) and a screw 784 extends through the two spaced-apart portions of block 780 to enable rotative adjustment of block 780 on the projecting end 778 of shaft 770. A second block 786 is adjustably mounted on the L-shaped extension 782 of block 780 by means of screws 788 which extend through slots 790 in the extension 782 of block 780 (FIG. 27). A stub shaft 792 is press-fitted in adjustable block 786. Screws 788 in slots 790 enable the eccentricity of shaft 792 relative to shaft 770 to be adjusted as desired.

Stub shaft 792 supports a pair of links 794, 796. Between links 794, 796, shaft 792 has a gear 798 keyed thereto. Gear 798 meshes with a second gear 800 supported on a pin 802. On each side of gear 800 there is supported on pin 802 the other end of links 794, 796 and also the upper ends of a pair of upright links 804, 806. The lower ends of links 804, 806 are supported by a fixedly supported shaft 808 to which a gear 810 is suitably keyed. Gear 810 meshes with gear 800. Shaft 808 is journaled at one end within end bearing plate 662 of sealing roll frame 654 (FIG. 25), and at its other end it is journaled in crossbar 652 of sealing roll frame 654. At the end of shaft 808 opposite gear 810 a small pinion 812 is fixed. Pinion 812 meshes with the drive gear 638 on the sealing roll 44.

It will be appreciated that by adjusting the eccentricity of shaft 792 which drives gear 798 relative to the end 778 of shaft 770, the extent to which gear 810 and thus shaft 808 are periodically accelerated and decelerated may be controlled. For example, if shaft 792 is coaxially aligned with shaft 770, it will merely rotate in response to rotation of the chain-driven sprocket. However, if block 786 is adjusted so that shaft 792 is eccentric relative to shaft 770, then when sprocket 122 rotates, gear 798 will not only rotate with shaft 792 but will also revolve about shaft 770 as an axis. As pin 792 revolves about the axis of shaft 770, links 794, 796 will be oscillated and thus cause gear 800 to oscillate a limited extent around the periphery of gear 810. Since gear 800 meshes with gear 798 and with gear 810, gear 810 will be periodically accelerated and decelerated. The decleration of gear 810 is timed by adjustment of slide 752 such that the speed of rotation of sealing rolls 42, 44 is reduced when the transverse ribs 636 of the sealing rolls come into registering relation to effect the seal 646 along the edge of the package being formed. This reduction in speed of the sealing rolls compensates for the increased area of the sealed edge 646 in relation to the side sealed edges 644 and thus allows the rolls sufficient time to effect a tight seal along edge 646.

Sequence of operation

The sequence of operation of the basic components of the machine is illustrated in FIGS. 61 through 66 and a timing diagram of such sequence of operation for the basic components of the machine is illustrated in FIG. 67. In FIGS. 61 through 66, some of the machine components are shown in a somewhat schematic way since these views are intended to illustrate primarily the operation of the machine, not specific details of construction of the various components.

Starting with the operation of the machine with the components in the positions illustrated in FIG. 61, it will be observed that the knife blade 278 is in the elevated position as is the metering head 16. The operation of forming a package has just been completed as is indicated by the package 642 which has just dropped from between the sealing rolls 42, 44. At this point in the operation of the machine, air is being directed through the orifices 610 and the air jets issuing from these orifices float the paper web 45 as it is advanced between the movable knife blade 278 and the stationary knife plate 245. At this point in the operation, each top valve 432 in metering head 16

has just closed and each bottom valve 434 is also closed to trap a predetermined quantity of sugar in each metering chamber 416. In this position, the metering head 16 is at top dead center, the position indicated at 180° on FIG. 67, and the cam follower 24 which actuates the metering head is riding on the lowermost portion of cam 20. In FIG. 62, the parts are illustrated at the point in the cycle designated 260° in FIG. 67. As is indicated on FIG. 67, the knife blade 278 has already sheared the paper web to provide the strip 38 and the paper folder 36 has descended with the head 16 to a position just prior to contacting the spring leaves 40. At this point, each dust trapdoor 30 is fully opened and each bottom valve 434 likewise opens to permit the slugs of sugar in each metering chamber 416 to drop downwardly toward the paper strip which is just beginning to be folded by the folder 36. In the machine illustrated, paper web 45 has a width sufficient to form a series of four sugar packets 642.

In the position of the parts illustrated in FIG. 63, the cycle has advanced to the position shown approximately at about 320° in FIG. 67 where the metering head 16 is approaching the bottom dead center position. The slugs of sugar have been deposited in the creased portion of the paper strip 38 as indicated and sealing of the side edges 644 of each packet adjacent the folded edge 648 has just begun. The lower valves 434 are about halfway closed and the dust trapdoors 30 are still open.

With the parts in the position shown in FIG. 64, the cycle has advanced to approximately the position shown between 35° and 40° on the timing diagram of FIG. 67. At this position, the metering head has just passed the dwell at bottom dead center and is beginning to ascend. Each bottom valve 434 has finished closing and each top valve 432 just begins to open to admit sugar to the metering chamber 416. Since the metering head 16 is beginning to ascend and bar 28 has shifted out of engagement with the dust trapdoors 30 (see FIG. 5), the dust trapdoors 30 close and a vacuum is applied to the region adjacent the upper open end of the package. This effectively extracts any sugar dust or other lightweight particles from the upper edge of the package which is just about to be sealed along its upper open end. The suction produced at the lower ends of trapdoors 30 also draws out of the packages being formed and from the atmosphere adjacent the trapdoors sugar dust that might otherwise be trapped in the seals around the edge of the package and thus produce leakage through improper seals or deposit on the sealing rolls and form a caramel.

The design of the machine takes advantage of the upward motion of the metering head 16 in filling the metering chambers 416. By filling the metering chambers 416 while the head is moving upwardly, the effective rate of filling is substantially greater than would be the case if the metering head remained stationary while being filled. This is true because the velocity of the sugar filling the metering chambers relative to the metering chambers is the velocity due to gravity plus the velocity of the metering head. This results in a further advantage in that the accuracy of metering the sugar is actually independent of the speed of the machine up to a predetermined machine speed. It will be appreciated that the speed of operation of upper and lower valves 432, 434 varies in accordance with the operating speed of the machine. Thus, as long as the metering chambers 416 are filled on the upstroke of the metering head, an increase in the speed of the machine not only causes valves 432, 434 to open and close at shorter time intervals, but also causes the metering chambers to fill more rapidly because the metering head 16 is moving upwardly more rapidly. Therefore, as long as the total top valve opening time is slightly longer than the time required to fill the metering chamber at any given speed of the machine, a change in the machine operating speed will not affect the accuracy of filling.

With the parts in the position shown in FIG. 65, the cycle has advanced to approximately the position shown

at about 90° on the timing diagram of FIG. 67. At this position, it will be observed that each metering chamber 416 is completely filled with sugar and each top valve 432 is just beginning to close. The metering head is moving upwardly and trapdoors 30 are still in the closed position at this time. Any particles of sugar that may have escaped from metering chambers 416 and sugar dust trailing the metered slug of sugar are retained in chutes 32 above trapdoors 30. These particles of course will be released with the sugar charge upon the next successive cycle of the machine. As is illustrated in FIG. 65, at this point in the cycle of the machine, air under pressure is being discharged through the orifices 610 over spring blades 40 and also from orifices 612 and 614 below the spring blades. The air issuing from orifices 612 and 614 serve to remove from the area of the upper edge of the package being formed any particles that might be floating in this vicinity just before the package is completely sealed. It will also be observed that the feed of paper web 45 has begun while the metering head 16 is still traveling upwardly.

With the parts in the position illustrated in FIG. 66, the cycle has progressed to approximately the position shown at 140° in FIG. 67. The metering head 16 is approaching the top dead center position and each top valve 432 has begun to close. Trapdoors 30 are still closed to retain in chutes 32 any particles that may have escaped from the metering chambers after the lower valves 434 closed. Sealing of the package is approaching completion and air is still being directed through the upper orifices 610 and the lower orifices 612 and 614 to maintain the sealing rolls free of any sugar dust that might otherwise accumulate and melt thereon. The various valves (not illustrated) for controlling the flow of pressurized air to the orifices 610, 612 and 614 on the manifold 580 are controlled by the cams 129a on jack shaft 116 through suitable microswitches and solenoids (not illustrated).

It will thus be seen that the machine herein disclosed is capable of producing perfectly sealed packages at a very high rate of production. Nevertheless, the machine is quite compact from the standpoint of size and requires relatively little power to operate it. It will be noted that the driving motor 70 is located on the top of the machine frame, and is coupled directly with the main drive shaft which is supported on the heavy upper platen 340. Platen 340 is mounted on the frame members 86 at opposite sides of the machine. Thus the torque of motor 70 and gear reducer 72 is transmitted directly through the flexible coupling 78 to the main drive shaft 76 that is journalled on the solid support provided by the heavy platen. This makes for a very rigid construction and minimizes the vibration in the machine.

As will be apparent from the showing in FIG. 2, the portion of the machine directly below the metering head 16, that is, the space below bearing plates 662, is unobstructed and thus ideally suited for accommodating a conveyor mechanism on which cartons may be arranged to receive the filled packages 642 as they are discharged from between the sealing rolls 42, 44. Thus, with this arrangement, cartons may be automatically directed straight through the lower portion of the machine without any interruption in its operation.

In connection with the operation of the metering head 16, an important feature of the present design resides in the manner in which the metering valves 432, 434 are operated. By forming cam slots 482 on opposite sides of cam 20 such that the slots 470 and 466 in levers 472 and 468, respectively, extend vertically when the valve members are in closed position. The arms 460 and 462 will not be reciprocated to shift these valves while the metering head 16 is reciprocating vertically. Thus, the closed positions of valves 432 and 434 are unaffected by the vertical travel of the metering head.

It is apparent that the ability to open and close valves 432, 434 while head 16 is reciprocating vertically accounts

10 for a large extent for the high rate of production which the machine is capable of achieving. Cam members 481, 483 can be so located relative to the high point of cam 20 to open and close valves 232, 234 at any desired point in the vertical travel of head 16. If upper valves 432 are opened immediately after lower valves 434 are closed, a maximum time interval is provided for filling metering chambers 416. Furthermore, by opening lower valves 434 on the downstroke of head 16, the extent of free fall of the sugar is minimized and the charge discharged from each metering chamber 416 is sharply defined at its leading and trailing ends (FIG. 62). This not only increases the rate at which the machine can be operated but also minimizes the tendency for the sugar to disperse or scatter as it drops downwardly into the packages being formed.

20 The design and operation of the metering head is important in another respect. Since the folders 36 are mounted directly on the metering head directly adjacent the outlets of the metering chambers, this design enables the product being packaged to be disposed directly into the package while it is being formed. This is clearly illustrated in FIGS. 63 and 64. From these showings, it will be observed that the lower end of the chute formed between the adjacent folders extends directly into the package being formed while the sugar is being discharged therefrom. This reduces to a minimum the free fall of the sugar and likewise reduces to a minimum the tendency for the sugar to scatter and disperse. This result is obtained only by having the metering head with the folders thereon reciprocating vertically so that on the upstroke of the metering head the sheet packaging material can be positioned between the folders and the spring leaves 40 and on the downward stroke of the metering head the sugar can be discharged from the metering chamber 416 substantially directly into the packages while they are being formed.

30 Another unique feature of the present machine which contributes substantially to the production of perfectly sealed packages at a very high rate comprises the trapdoor 30. This trapdoor 30 has a dual function. When it is closed, as shown in FIG. 9, it traps any particles of product being packaged that might have a tendency to drop downwardly into the zone where the packages are being formed and sealed or onto the sealing rolls. Furthermore, when trapdoor 30 is closed, it applies a vacuum to the region immediately adjacent the packages as they are being formed to remove from the surrounding area any small particles of sugar, dust, etc. that might be present and interfere with the complete sealing of the packages around their edges. Of course, the action of the dust trapdoors 30 in removing dust particles from around the packages as they are being formed is also enhanced by the manifold 580 with its orifices 610, 612 and 614. These orifices direct streams of pressurized air closely adjacent the edges of the packages that are being formed and since the manifold itself is located very closely to the edges of the sealing rolls, the air streams issuing from orifices 612 and 614 also prevent dust, sugar, etc., which might escape from the packages, from accumulating on the sealing rolls.

40 Another important feature of the machine resides in the provision of the distributor 14 and its telescopic connection with the outlet tube 12 of the stationary hopper 10. Since distributor 14 reciprocates vertically with metering head 16, there is always present immediately above the metering chambers 416 a loose mass of product to be packaged, which accounts for the fact that these metering chambers will fill very rapidly upon the opening of the upper valves 432.

50 The sealing roll construction and drive likewise facilitates operation of the machine to form perfectly sealed packages at a high rate. As pointed out previously, the operation of the sealing rolls can be synchronized with the operation of the folder to assure the proper location of the top seam 646 of the package by shifting the idler

rolls 738, 740 even while the machine is operating. Likewise, the amount of pressure exerted by the sealing rolls on the edges of the packages being formed can be controlled as desired by adjusting screws 682 and 696 to thereby vary the clearance between the peripheries of the sealing rolls very accurately and also vary the tension in springs 694 to exert the desired sealing pressure while permitting the rails to separate if necessary. In this connection, the provision of the slip clutch 700, 706 which assures the perfect synchronization at all times between the sealing rolls and the remaining operating mechanisms of the machine is a highly desirable feature. If rotation of the sealing rolls is obstructed in some fashion, when the clutch re-engages the sealing rolls will automatically be synchronized with the other mechanisms.

I claim:

1. In a packaging machine, the combination comprising a motor driven shaft and the following mechanisms operatively connected with the motor driven shaft to be driven thereby in timed sequence: a mechanism for feeding sheet packaging material, a folding mechanism for folding the sheet packaging material to form packages, means for filling the packages being formed with the product to be packaged and a pair of sealing rolls for sealing the edges of the packages being formed, the means operatively connecting said shaft with the sealing rolls comprising a sprocket associated with said motor driven shaft, a sprocket associated with said sealing rolls for driving the same, an endless chain trained around said two sprockets and having opposed runs, a pair of idler sprockets engaged one with each of the opposed runs of the chain and means for shifting said pair of idler sprockets transversely of said runs of the chain to thereby vary the length of said opposed runs relative to each other and thus rotate the sprocket associated with the sealing rolls relative to the sprocket associated with the motor driven shaft.

2. The combination called for in claim 1 wherein the sealing rolls are supported on parallel axes for rotation in opposite directions, the folding mechanism being adapted to fold a strip of said sheet packaging material and feed it folded edge foremost between said sealing rolls, the sealing rolls having radially aligned circumferentially extending ribs for sealing the side edges of the packages being formed and also having longitudinally extending ribs which are adapted to register with one another when the sealing rolls are rotated to seal the edge of the package opposite the folded edge.

3. The combination called for in claim 1 including a support shiftable in a direction transversely of said opposed runs of said chain, said idler sprockets being mounted on said support for movement in unison therewith.

4. In a packaging machine of the type having a folder adapted to fold a strip of sheet packaging material and feed the folded strip between a pair of sealing rolls to form packages, that improvement which comprises a drive shaft operatively connected with the sealing rolls, the means operatively connecting said drive shaft and sealing rolls including a drive sprocket associated with the drive shaft, a driven sprocket associated with the sealing rolls, an endless chain trained around the two sprockets and having a pair of opposed runs extending therebetween, a pair of idler sprockets engaging each with one run of the chain, a common support for said pair of idler sprockets and means mounting said support for movement in a direction transversely of said runs of the chain for increasing the effective length of one of said runs and shortening the effective length of the other run to thereby rotate said driven sprocket relative to said drive sprocket.

5. The combination set forth in claim 4 including a pair of fixedly supported idler sprockets engaging each run of said chain on opposite sides of each of the idler sprockets.

6. In a packaging machine, the combination comprising

ing a drive shaft, a plurality of means operatively driven by the drive shaft in timed sequence including a mechanism for feeding sheet packaging material, a mechanism adapted to fold the sheet material to form packages, a mechanism for filling the packages as they are being formed and a roll mechanism for sealing the edges of the packages, a clutch interposed in the operative connection between the drive shaft and the sealing roll mechanism, said clutch comprising a rotary driving member, a rotary driven member and resiliently biased detent means forming a driving connection between said rotary members which is adapted to be disengaged upon a predetermined resistance to rotation applied to said driven member, said detent means being designed to interconnect said rotary clutch members only in a single predetermined relative position of the two clutch members such that in the event the driving connection between the two clutch members is broken, the two clutch members are adapted to re-engage only when the drive member rotates to the same position relative to the driven member at which the driving connection therebetween was broken to thereby maintain the timed sequence of operation of the sealing roll mechanism relative to said other mechanisms.

7. The combination set forth in claim 6 wherein said clutch members comprise a pair of axially aligned members, one of said members having a pair of spring biased detents therein and the other having sockets therein registering with said detents and in which said detents are adapted to engage to establish a driving connection between the two clutch members, one of said detents and its associated socket being spaced radially from the axis of rotation of said clutch member a distance different from the radial spacing of the other detent and socket from the axis of rotation of the clutch members.

8. In a packaging machine, the combination comprising a vertically reciprocable metering head having a metering chamber therein, a pair of valves for closing the upper and lower ends of the metering chamber, a package forming mechanism adapted to form packages from sheet material with an open upper end disposed vertically below the metering chamber, means providing a supply of product to be packaged communicating with the upper valved end of the metering chamber and which is adapted to flow into the metering chamber when the upper valve is opened and means for alternately opening and closing said valves in timed relation with and during the vertical reciprocation of said metering head to successively fill the metering chamber from said supply and then discharge the contents of the metering chamber downwardly by gravity into the open end of the package therebelow.

9. The combination set forth in claim 8 wherein said last-mentioned means are adapted to open the top valve when the metering head is moving upwardly.

10. The combination set forth in claim 8 wherein said valves comprise generally horizontally slidable valve members.

11. The combination set forth in claim 8 wherein the means for opening and closing the valves comprise a pair of levers each supported for pivotal movement about a fixed horizontal axis, each lever having a slot therein spaced from the pivot axis thereof, each valve having a horizontally extending arm, the free end of each arm engaging in one of said slots such that when the levers are pivotally actuated in opposite directions the valves are opened and closed, said free ends of the arms being movable vertically in said slots in response to vertical reciprocation of the metering head and means for pivotally reciprocating said levers in timed relation with the vertical reciprocation of the metering head such that each slot extends in a direction parallel to the path of travel of the metering head for a predetermined timed interval during each reciprocation of the head to retain said valves in closed positions.

12. The combination set forth in claim 11 wherein said means for reciprocating said levers comprise a pair of cams rotated in synchronism with the reciprocation of said head and cam followers on said levers engaging said cams.

13. The combination set forth in claim 8 wherein said means providing a supply of product to be packaged comprises a fixed receptacle for containing said product above said metering head, said fixed receptacle having a depending outlet, means on said metering head forming a receptacle communicating with the upper valved end of the metering chamber, said second receptacle having a volume substantially greater than the metering chamber and being telescopically connected with the depending outlet on the first receptacle.

14. The combination set forth in claim 13 including means for applying a suction to the telescopic connection between said two receptacles.

15. The combination set forth in claim 8 wherein said metering head includes means forming a chute extending downwardly from the lower valved end of the metering chamber and means operated in synchronism with the vertical reciprocation of the metering head for closing the lower end of said chute during at least a portion of the time when the lower valve is closed.

16. The combination set forth in claim 13 including means for applying a suction to the zone adjacent the outlet of said chute upon closing of the chute.

17. The combination set forth in claim 16 wherein said means for closing the lower end of said chute comprises a door member pivotally supported on the chute for movement about a horizontal axis.

18. The combination set forth in claim 16 wherein said means for closing the lower end of the chute comprises a wall portion of the chute pivotally supported on a horizontal axis adjacent its upper end such that its lower end can be swung into generally sealing engagement with an opposite wall portion of the chute.

19. The combination set forth in claim 18 wherein the pivotally supported wall portion of the chute comprises a conduit open at its lower end and having its upper end adapted to be connected to a source of suction.

20. The combination set forth in claim 19 including a suction conduit positioned to register with the upper end of said first mentioned conduit when the movable wall portion is in said position closing the lower end of the chute.

21. The combination set forth in claim 8 wherein the metering head is provided with vertical apertures therein for discharging in a downwardly direction any product that might escape from the metering chamber adjacent the valves, a receptacle below and registering with said apertures and connected to a source of vacuum.

22. The combination set forth in claim 8 wherein said package forming means includes a downwardly depending nose portion on said metering head adjacent the lower end of said metering chamber adapted to engage a sheet of packaging material below the metering head and fold it along a central portion thereof.

23. The combination set forth in claim 22 wherein said package forming means also includes a pair of horizontally disposed spring leaves positioned below said nose portion for supporting said sheet packaging material, said spring leaves being adapted to flex downwardly when engaged by said nose portion to fold the opposite free edge portions of the sheet material upwardly along the nose portion.

24. The combination set forth in claim 23 including a support on which said spring leaves are mounted adjacent their opposite free edges, said support including a manifold portion having apertures therein directed inwardly toward the path of travel of the nose portion from opposite sides thereof and means for directing air under pressure to said apertures in said manifold portion.

25. The combination set forth in claim 24 wherein said apertures are located above and below said spring leaves and closely adjacent the horizontal plane thereof.

26. The combination set forth in claim 23 wherein said package forming means also includes a pair of adjacently positioned sealing rolls rotatably supported on parallel axes and between which the folded sheet material is adapted to be directed by the descending nose portion of the metering head.

27. The combination set forth in claim 26 wherein the sealing rolls are disposed below said spring leaves and including a manifold member, said spring leaves having free inner adjacent edges adapted to be engaged by said nose portion and having outer edges supported by said manifold member, said manifold member being connected with a source of air under pressure and having apertures therein for directing pressurized air above and below said spring leaves to maintain the portions of the sealing rolls between which the folded sheet is directed free from unwanted particles of the product being packaged.

28. In a packaging machine of the type which includes a metering head for discharging successive charges of product to be packaged vertically downwardly onto a sheet of packaging material which is folded and directed downwardly between a pair of sealing rolls for sealing the edges of the package with the product therebetween, that improvement which comprises a manifold member disposed above and closely adjacent said sealing rolls, a pair of horizontally disposed spring leaves lying in generally the same plane and having outer opposed edges supported on said manifold member, said spring leaves having inner adjacent free edges disposed to align generally with the folded edge of the sheet packaging material, said manifold member having apertures therein for directing pressurized air above and below said spring leaves in a direction transversely of the axes of said sealing rolls.

29. The combination set forth in claim 28 wherein at least some of said apertures are located below the plane of said spring leaves and have their axes inclined downwardly in a direction generally between the sealing rolls.

30. A packaging machine comprising a frame, a mechanism for feeding a web of sheet packaging material in a generally horizontal direction, a knife head on the frame through which said web of packaging material is adapted to be fed and sheared into successive transverse strips, a pair of sealing rolls disposed below the strip cut from said web by said knife head, a metering head and strip folder mounted for vertical reciprocation above said sealing rolls, a receptacle fixed on said frame and adapted to contain a supply of product to be packaged, means forming an intermediate product supply chamber mounted to reciprocate with said metering head and connected with said receptacle for providing a constant supply of product from said receptacle to said metering head, said metering head having means thereon for discharging successive charges of said product from said intermediate supply chamber downwardly onto said strip of said packaging material, said strip folder depending from said metering head and adapted when the metering head moves downwardly to fold the cut strip and feed it downwardly between the sealing rolls.

31. The combination set forth in claim 30 including means for driving said feeding mechanism, said knife head, sealing rolls and metering head, said driving means being located on said frame other than below said sealing rolls.

32. The combination set forth in claim 30 including a relatively heavy upper platen fixedly mounted on said frame, a pair of depending guide posts on said platen, a lower platen vertically reciprocable on said guide posts, said metering head being mounted on said lower platen to reciprocate therewith, means biasing the lower platen and the metering head upwardly and means on said frame for overcoming the biasing means and driving the platen and metering head downwardly.

33. The combination set forth in claim 32 wherein said

driving means comprise a shaft journalled on said frame for rotation about a horizontal axis, a cam on said shaft and a cam follower mounted on said lower platen and operatively associated with said cam.

34. The combination set forth in claim 32 wherein the receptacle and the intermediate supply chamber have telescopically engaged vertical conduit portions for supplying product from the receptacle to the vertically reciprocating intermediate supply chamber.

35. The combination set forth in claim 30 wherein said feed mechanism includes a constantly rotating shaft having a crank arm thereon, an oscillatable shaft supported on an axis parallel to the axis of the rotatable shaft and having a crank arm thereon longer than the first crank arm, a link connecting said crank arms, roll means for feeding said sheet material, means operatively connecting said oscillatable shaft with said roll means, said last-mentioned means comprising clutch means for driving said roll means only in response to oscillation of the second shaft in one direction.

36. The combination set forth in claim 34 wherein the effective length of the second crank arm is adjustable to vary the extent of oscillation of the second shaft.

37. In a packaging machine of the type including a pair of feed rolls between which sheet material is adapted to be fed to seal the edges of the packages formed from said sheet material, that improvement which comprises means forming a fixed journal for the opposite ends of one of the sealing rolls, means forming a journal for the opposite ends of the other sealing roll, said second journal means being shiftable toward and away from the axis of the first sealing roll, means resiliently biasing the second journal means toward the first journal means to urge the second sealing roll toward the first sealing roll and adjustable stop means for limiting the extent of movement of the second sealing roll toward the first to establish a predetermined clearance between the sealing rolls.

38. The combination set forth in claim 37 wherein said last-mentioned means includes a micrometer screw adjustment means.

39. In a packaging machine, the combination comprising a pair of sealing rolls between which packages are adapted to be fed for sealing the edges of the packages, a shaft supporting each sealing roll, means journaling the opposite ends of one shaft for rotation in a fixed position, means journalling the opposite ends of the other shaft for movement toward and away from the first shaft, spring means biasing the journal means for the second shaft toward the first shaft and adjustable stop means interposed between said two journal means for limiting the extent of movement of said second shaft toward said first shaft for establishing a predetermined adjustable clearance between the peripheries of said sealing rolls.

40. The combination set forth in claim 39 wherein the journal means for the second shaft are pivotally supported about an axis parallel to and spaced from the axis of the second shaft.

41. In a packaging machine, the combination comprising a vertically reciprocable metering head having a plurality of metering chambers therein, a pair of valves for closing the upper and lower ends of each metering chamber, means for positioning a strip of sheet packaging material below the metering head, said metering head having means thereon which, when the metering head descends, is adapted to fold said strip lengthwise to initiate the forming of a package having an open upper end disposed below each of the metering chambers, means providing a supply of product to be packaged communicating with the upper valved end of each metering chamber and which is adapted to flow into each metering chamber when the upper valve thereof is opened, and means for alternately opening and closing in unison said upper valves and said lower valves in timed relation with and during the vertical reciprocation of the metering head to successively fill the metering chambers from said supply and then discharge the contents of each

metering chamber downwardly by gravity into the open end of the package being formed therebelow.

42. The combination set forth in claim 41 including a pair of sealing rolls disposed below said metering head, said folding means on the metering head being adapted to feed said folded strip downwardly between said sealing rolls.

43. A packaging machine comprising a frame, a receptacle fixed on said frame and adapted to contain a supply of product to be packaged, a metering head mounted on said frame for vertical reciprocation, said metering head having a valve controlled metering chamber therein, an intermediate product supply chamber mounted to reciprocate with said metering head and having a telescopic connection with said fixed receptacle for providing a constant supply of product from said receptacle to said metering head, said intermediate product supply chamber being of a substantially larger volume than said metering chamber, and valve means for controlling the flow of product from said receptacle to said intermediate supply chamber.

44. The combination set forth in claim 43 including means controlling said valve means to maintain said intermediate product supply chamber only partially filled.

45. The combination set forth in claim 43 including means for feeding sheet package forming material to a position below said metering head and means reciprocable with said metering head for initiating the formation of a package from said sheet material as the metering head descends, whereby to receive the product discharged from the metering chamber.

46. The combination set forth in claim 43 wherein said metering head is provided with a plurality of metering chambers therein, said intermediate product supply chamber having a plurality of outlets therein for conducting the product to be packaged to each of said metering chambers.

47. The method of packaging material which comprises feeding a strip of sheet packaging material in a generally horizontal position to a package filling and forming station, folding the strip throughout its extent in a direction transverse of the feed direction to form the strip into a generally channel-shaped receptacle which is open at its upper end, moving the channel-shaped strip downwardly as it is being folded and depositing product to be packaged vertically downwardly into the receptacle after the folding operation has been initiated.

48. In a packaging machine of the type wherein sheet packaging material is adapted to be folded to form a package and the package filled with product the combination of a metering head mounted for vertical reciprocation, means for reciprocating said head, means on the head for discharging in a vertically downwardly direction successive metered charges of the product, means for positioning below the head when the head is in an elevated position a strip of packaging material and means independent of said product mounted on the head and adapted to fold said strip throughout its entire extent in one direction into an upwardly-opening channel-shaped receptacle when the head moves downwardly.

49. In a packaging machine the combination comprising a vertically reciprocable metering head having a plurality of metering chambers therein, each metering chamber having an inlet and an outlet, a pair of valves for closing and opening the inlet and outlet of each chamber, means for positioning a strip of sheet packaging material below the metering head, said metering head having means thereon which when the metering head descends is adapted to fold said strip throughout its length to initiate the forming of a package having an open end below each of the metering chambers, means providing a supply of product to be packaged communicating with the valved inlet of each metering chamber and which is adapted to fill each metering chamber when the inlet valve thereof is opened and means for alternately open-

ing and closing the inlet and the outlet valves in timed relation with the vertical reciprocation of the metering head to successively fill the metering chamber from said supply and then discharge the contents of each metering chamber into the open end of the package being formed therebelow.

50. In a packaging machine the combination comprising a vertically reciprocable metering head having a metering chamber therein, said metering chamber having an inlet and an outlet, a pair of valves for opening and closing said inlet and outlet of the metering chamber, a package forming mechanism adapted to form packages from sheet material with an open end disposed adjacent said outlet, means providing a supply of product to be packaged communicating with the valved inlet of the metering chamber and which is adapted to fill the metering chamber when the inlet valve is opened and means for alternately opening and closing said valve in timed relation with the vertical reciprocation of the metering head to successively fill the metering chamber from said supply and then discharge the contents of the metering chamber into the open end of the package therebelow.

51. In a packaging machine of the type wherein sheet packaging material is adapted to be folded to form a package and the package filled with a product, the combination comprising a mechanism for feeding a strip of said packaging material to a package filling and forming station and for positioning said strip at a predetermined location at said station in a generally horizontal plane, said station including a generally vertically reciprocating strip folding mechanism disposed above the location of the strip of packaging material, said strip folding mechanism including abutments spaced apart along a line extending transversely of the direction of feed of said strip and substantially throughout the transverse length of the strip, said abutments being adapted, when the folding mechanism moves downwardly, to engage the transversely extending central portion of the strip and displace said central portion downwardly to thereby fold the strip throughout its length along said transversely extending central portion into a trough-shaped receptacle which is open at the top and which is closed at the bottom by said folded central portion, said station also including means for depositing the product to be packaged into said receptacle through the open end thereof between said abutments and a sealing mechanism positioned below said folding mechanism and adapted to engage opposed, upwardly extending portions of the trough-shaped strip as the latter is displaced downwardly by said abutments and draw said opposed portions inwardly towards each other in contacting sealed engagement.

52. The combination set forth in claim 51 wherein the abutments cooperate with the strip as it is being folded to close opposite ends of the receptacle being formed and thereby confine the product therein.

53. The combination called for in claim 51 wherein said depositing means comprises a metering head mounted to reciprocate with said folding mechanism and having an outlet opening for discharging the product into said receptacle.

54. The combination set forth in claim 48 wherein said discharging means on the head are adapted to discharge product into said package through the opening therein when the head moves downwardly.

55. The combination set forth in claim 48 wherein the metering head is provided with an outlet for the product, said folding means being located below and adjacent said outlet.

56. The combination set forth in claim 55 wherein said folding means form a chute extending downwardly from said outlet.

57. The combination set forth in claim 48 wherein the metering head is provided with a row of spaced outlets thereon through which the product is discharged, said folding means being disposed between said outlets.

58. The combination set forth in claim 57 wherein said folding means form a chute extending downwardly from each outlet.

59. The combination set forth in claim 51 wherein said depositing means are adapted to deposit product into said receptacle on the downstroke of said folding mechanism.

60. The combination set forth in claim 53 wherein said abutments are located below and adjacent opposite sides of said outlet.

10 61. The combination set forth in claim 60 wherein said abutments form a chute extending downwardly from said outlet.

15 62. The combination set forth in claim 51 wherein the depositing means is provided with a row of outlets thereon spaced laterally along said transverse line and through which the product is discharged, there being at least one abutment disposed between each pair of successive outlets to divide the strip into a plurality of laterally successive receptacles when the abutments engage the strip.

20 63. The combination set forth in claim 62 wherein successive pairs of abutments form a chute extending downwardly from each outlet.

25 64. The combination set forth in claim 52 wherein said sealing mechanism comprises a pair of tangentially opposed sealing rolls between which the package is directed by said abutments, said sealing rolls having axially spaced peripheral ribs thereon for drawing said opposed portions of the strip into contacting sealed engagement, said rolls having recesses on the outer periphery thereof which extend axially between said ribs, said abutments being spaced apart a distance less than the spacing between said ribs and being positioned to project downwardly into said recesses on the downstroke of the folding mechanism to direct the folded edge of the strip between opposed peripheral ribs on the sealing rolls.

30 65. The combination set forth in claim 64 wherein the lower end portions of said abutments taper in a downward direction to a generally pointed free end.

35 66. The combination set forth in claim 65 including yieldably resilient support means disposed above said sealing mechanism and upon which said strip of sheet packaging material is adapted to be positioned by said feeding and positioning mechanism, said support means acting to maintain the folded strip in engagement with said abutments as the abutments displace the strip downwardly.

40 67. The combination set forth in claim 65 including a pair of spring leaves disposed above said sealing rolls and upon which said strip of sheet packaging material is adapted to be positioned as it is engaged by the downwardly moving abutments.

45 68. The combination set forth in claim 67 including means for directing streams of pressurized air between said spring leaves and the sealing rolls for maintaining the sealing rolls free of material being packaged.

50 69. The combination set forth in claim 53 wherein said metering head includes means forming a chute extending downwardly from said outlet and means operated in synchronism with the vertical reciprocation of the metering head for closing the lower end of said chute during at least a portion of each vertical stroke of the metering head.

70 70. The combination set forth in claim 69 including means for applying a suction to the zone exterior of and adjacent the lower end of said chute upon closing of the chute.

75 71. The combination set forth in claim 70 wherein said means for closing the lower end of said chute comprises a door member pivotally supported on the chute for movement about a horizontal axis.

72. The combination set forth in claim 70 wherein said means for closing the lower end of the chute comprises a wall portion of the chute supported so that it can be moved into generally sealing engagement with an opposite wall portion of the chute.

73. The combination set forth in claim 72 wherein the movable wall portion of the chute comprises a conduit open at its lower end and having its upper end adapted to be connected to a source of suction.

74. The combination set forth in claim 73 including a suction conduit positioned to register with the upper end of said first mentioned conduit when the movable wall portion is in said position closing the lower end of the chute.

75. The combination set forth in claim 62 wherein said sealing mechanism is adapted to divide the trough-shaped strip into a plurality of laterally successive compartments.

76. The combination set forth in claim 75 including means for severing said laterally successive compartments from one another to divide the strip into a plurality of packets.

77. The combination set forth in claim 51 including means for pressing the strip of packaging material upwardly against the abutments as the abutments move downwardly into engagement with the strip.

78. The combination set forth in claim 53 wherein the metering head has a metering chamber therein, said metering chamber being provided with an inlet opening, a pair of valves for opening and closing said inlet and outlet openings, means providing a supply of product to be packaged communicating with the valved inlet opening of the metering chamber and which is adapted to flow into said metering chamber when the valved inlet opening is opened and to flow from said metering chamber through said outlet opening when the latter is open and means for alternately opening and closing said valves in timed relation with and during the vertical reciprocation of said metering head to successively fill the metering chamber from said supply and then discharge the contents of the metering chamber into the open end of the receptacle formed therebelow by said trough-shaped strip.

79. The combination set forth in claim 78 wherein said inlet opening opens vertically upwardly at the upper end of said chamber and said outlet opening opens vertically downwardly at the lower end of said chamber.

80. The combination set forth in claim 79 wherein the valve operating means are adapted to maintain the top valve open during at least a portion of the upward stroke of the metering head.

81. The combination set forth in claim 79 wherein said valves are slidably disposed in fixed, generally-horizontal planes and the metering chamber includes a generally vertical wall which is displaceable in a horizontal direction for varying the size of said chamber.

82. The combination set forth in claim 79 wherein the means for opening and closing the valves comprise a pair of levers each supported for pivotal movement about a fixed horizontal axis, each lever having a slot therein spaced from the pivot axis thereof, each valve having a horizontally extending arm, the free end of each arm engaging in one of said slots such that when the levers are

5 pivotally actuated in opposite directions the valves are opened and closed, said free ends of the arms being movable vertically in said slots in response to vertical reciprocation of the metering head and means for pivotally reciprocating said levers in timed relation with the vertical reciprocation of the metering head such that each slot extends in a direction parallel to the path of travel of the metering head for a predetermined timed interval during each reciprocation of the head to retain said valves in closed positions.

10 83. The method of packaging a product which comprises, feeding a strip of sheet packaging material in a horizontal position to a package filling and forming station, pressing said strip downwardly at said station throughout the length of its transversely extending central portion by means of abutments spaced apart along a line extending transversely of the feed direction of said strip so as to fold the portions of the strip on opposite sides of said transversely extending central portion relatively upwardly throughout the transverse length of the strip and thereby form the strip into a generally channel-shaped trough, moving the trough-shaped strip downwardly as it is being folded, depositing the product to be packaged into said trough between said abutments and thereafter bringing the opposite side portions of the trough laterally beyond the abutments into contacting sealing engagement to form a package for the product.

15 84. The method called for in claim 83 including the step of displacing the opposite side portions of the trough progressively closer together as the strip is moving downwardly to progressively close the trough in an upward direction.

20 85. The method set forth in claim 83 wherein the step of depositing the product is performed by moving a product discharge outlet downwardly with the downwardly moving folded strip.

25 86. The method called for in claim 83 including the step of pressing the paper strip upwardly against the downwardly moving abutments so that the spaced abutments cooperate with the opposite side portions of the trough to divide the trough into a plurality of successive compartments separated by said abutments.

30 87. The method called for in claim 83 including the step of applying a suction to the open upper end of the trough after the product has been fully deposited therein.

35 88. The method called for in claim 83 wherein the product is deposited into said trough as the folded trough is moving downwardly.

pivotally actuated in opposite directions the valves are opened and closed, said free ends of the arms being movable vertically in said slots in response to vertical reciprocation of the metering head and means for pivotally reciprocating said levers in timed relation with the vertical reciprocation of the metering head such that each slot extends in a direction parallel to the path of travel of the metering head for a predetermined timed interval during each reciprocation of the head to retain said valves in closed positions.

40 83. The method of packaging a product which comprises, feeding a strip of sheet packaging material in a horizontal position to a package filling and forming station, pressing said strip downwardly at said station throughout the length of its transversely extending central portion by means of abutments spaced apart along a line extending transversely of the feed direction of said strip so as to fold the portions of the strip on opposite sides of said transversely extending central portion relatively upwardly throughout the transverse length of the strip and thereby form the strip into a generally channel-shaped trough, moving the trough-shaped strip downwardly as it is being folded, depositing the product to be packaged into said trough between said abutments and thereafter bringing the opposite side portions of the trough laterally beyond the abutments into contacting sealing engagement to form a package for the product.

45 84. The method called for in claim 83 including the step of displacing the opposite side portions of the trough progressively closer together as the strip is moving downwardly to progressively close the trough in an upward direction.

50 85. The method set forth in claim 83 wherein the step of depositing the product is performed by moving a product discharge outlet downwardly with the downwardly moving folded strip.

55 86. The method called for in claim 83 including the step of pressing the paper strip upwardly against the downwardly moving abutments so that the spaced abutments cooperate with the opposite side portions of the trough to divide the trough into a plurality of successive compartments separated by said abutments.

60 87. The method called for in claim 83 including the step of applying a suction to the open upper end of the trough after the product has been fully deposited therein.

65 88. The method called for in claim 83 wherein the product is deposited into said trough as the folded trough is moving downwardly.
